Inventor:
A. W. McCLEARY

By Earl M. Sinclair
Atty.

UNITED STATES PATENT OFFICE.

ALFRED W. McCLEARY, OF DES MOINES, IOWA.

HOLDER FOR SWINGING DOORS.

Application filed April 18, 1922. Serial No. 554,868.

To all whom it may concern:

Be it known that I, ALFRED W. McCLEARY, a citizen of the United States of America, and resident of Des Moines, Polk County, Iowa, have invented a new and useful Holder for Swinging Doors, of which the following is a specification.

The object of this invention is to provide an improved holding device adapted to be engaged by the free marginal portion of a swinging door as the door is moved to open position, said device being moved by such engagement into position for holding the door in its open position.

15 A further object of this invention is to provide an improved rotary holding device adapted for automatic latching or holding engagement with a swinging door to hold the door in open position until such time as it is manually released.

20 A further object of this invention is to provide an efficient holding device for swinging doors which is sure in operation, simple of construction and not apt to get out 25 of order.

25 My invention consists in the construction, arrangement and combination of elements hereinafter set forth, pointed out in my claims and illustrated by the accompanying 30 drawing, in which—

Figure 1 is an elevation, partly in section, showing my improved device mounted in position for practical use, a portion of a door being indicated by dotted lines in position for engagement with the device. Figure 2 is a plan of the same elements, the position of the device after engagement by the door being indicated by dotted lines.

35 In the construction of the device as shown 40 the numeral 10 designates a tubular support, such as a section of gas pipe, adapted to be mounted in a vertical position in the ground or in a cement driveway adjacent a building such as a garage having swinging doors with 45 which the device is to be used, said tubular support projecting above the surface to a point somewhat below the horizontal plane of the lower margin of the door, such as 11. The tubular support 10 is located near the 50 arc through which the free margin of the door 11 travels in moving from closed to open position, such arc being indicated by the dotted line 12 in Figure 2. The support 10 is threaded exteriorly at its upper end 55 and a cap 13 is adapted to be screwed there-

on, which cap is centrally apertured for the passage of a stem 14 therethrough. The stem 14 preferably extends a material distance into the tubular support 10 and is formed at its lower end with an enlargement or head 15 fitting rather snugly within the support, so that by such engagement and the engagement of the upper portion of the stem with the cap 13, the stem is held against lateral movement and maintained in upright position, but is permitted to rotate freely in the support and cap. A cross-head 16 is secured in any desired manner to the projecting upper end of the stem 14. In this instance the upper end portion of the stem is threaded and the cross-head is apertured and mounted thereon and held firmly between nuts 17, 18 screwed on said threaded portion, in contact with opposite faces of said cross-head. The cross-head 70 75 80 85 90 95 100 105 110

16 is formed at its ends with upturned integral arms 19, 20, on which are rigidly mounted collars 21, 22. Rotatively mounted on the upturned arms 19, 20 and supported by the collars 21, 22 are rollers 23, 24, which are held in place by riveting or upsetting the upper ends of the arms, at 25, 26, or by any other suitable means. In practical use one of the holding devices is mounted adjacent the path of travel of each of the doors and at the desired or necessary limit of opening movement of the door. When the door such as 11 is moved to open position, its free margin traveling through an arc on the line 12 in the direction of the arrow *a* in Figure 2, the outer face of the door contacts one or another of the rollers 23, 24, it being understood that said rollers occupy a horizontal plane above the bottom margin of the door and that the cross-head 16, support 10, cap 13 and nuts 17, 18 lie wholly below the plane of the bottom of the door, except for the upturned arms 19, 20 of said cross-head, as clearly shown in Figure 1. Such engagement of the door with one of the rollers 23, 24 produces a rotary movement of the cross-head and members carried thereby, on the axis of the stem 14, the engaged roller having rolling contact with the outer face of the door during such movement. The line 12 passes between the rollers 23, 24 when the cross-head is in a position radially of the circumference of which said line is an arc, so that the free margin of the door may pass between 110

said rollers and come to rest in a position substantially at right angles to the cross-head and extending across and above the same, as indicated by dotted lines in Figure 2, the axes of the rollers having moved through arcs indicated by the dotted lines 27 and 28 in said figure. It is obvious that continued pressure on the door in the direction of the arrow *a* will not tend toward further rotary movement of the cross-head, which is then at a position of dead-center relative to the door, and that closing movement of the door will be prevented by the other roller opposite to the one first engaged. 15 This engagement and automatic locking of the door is automatic and is accomplished by and through the engagement during opening of the door, regardless of the initial position of the cross-head and rollers, unless 20 it happen that they be already in a position of dead-center when the engagement is initiated. In such event it may be necessary for the operator to give a slight turn to the cross-head before the holding engagement can be effected. To release the door, 25 it is necessary to turn the cross-head manually to substantially the position shown by solid lines in Figure 2, so that the door may clear the innermost roller, in this instance 30 23, and pass between them out of the range of the cross-head, in a direction opposite to the arrow *a*.

The support 10 may be positioned by embedding it in cement or other plastic sub-

stance, or by driving it into the earth by 35 blows applied to upper end of stem 14.

I claim as my invention—

1. A holding device for swinging doors, comprising a tubular support, a cap adapted to be screwed on the upper end of said support, a stem loosely mounted through said cap and formed with a head on its lower end freely engaging the inner walls of said support at a distance below said cap, a cross-head fixed to the upper end of said stem, and integral spaced upstanding arms on said cross-head. 45

2. A holding device for swinging doors, comprising a tubular support, a cap adapted to be screwed on the upper end of said support, a stem passing loosely through said cap and projecting a material distance within said support, said stem being formed with a head on its lower end portion loosely engaging the inner walls of the support, said stem being threaded at its upper end, a cross-head formed with an aperture receiving said stem, nuts screwed on said stem on opposite sides of and contacting said cross-head, said cross-head being formed with 55 spaced upstanding arms, and rollers journaled on said arms, said rollers lying in a horizontal plane above the stem and support. 60

Signed at Des Moines, in the county of 65 Polk and State of Iowa, this 15th day of April, 1922.

ALFRED W. McCLEEARY.
